UNITED STATES PATENT OFFICE

2,627,735

LIQUID DISPENSING CUP

Carl J. Dexter, Battle Ground, Ind.

Application May 12, 1949, Serial No. 92,829

3 Claims. (Cl. 65—13)

1

This invention relates to a drinking cup.

The chief object of this invention is to provide a drinking cup which is intended to displace the use of the so-called drinking tube utilized by bed-fast patients.

The present invention also is particularly adapted for children's use. It is also particularly adapted for use by persons who are extremely nervous or who are afflicted with palsy.

The drinking cup of the present invention is not only adapted for the drinking of clear liquid but may be utilized for the drinking of thicker liquid, such as soup, etc., wherein some solids are embodied and this for bed-fast patients' use is extremely advantageous because the so-called drinking tube will clog and not pass such solids. Such a drinking vessel, therefore, permits one hand use and by a patient without nurse attendance during the drinking operation.

Another object of this invention is to provide a cup for drinking purposes which is substantially splash or spill proof.

The chief feature of the present invention resides in the provision of an indentation in the side of the cup immediately contiguous to and below the discharge spout, the side spout being formed by extending upwardly the adjacent side portions of the cup and then bridging these elevated side portions with a partial cover, the spout being formed as stated between the two portions specified.

Another feature of the invention resides in providing an inwardly directed flange about the portion of the periphery that is not occupied by the aforesaid cover, which flange prevents spilling of the cup content in the processing of drinking or in the act of lifting the cup from a support such as a table or tray and its replacement to its original position.

The cup indentation below the aforesaid spout permits the closer fitting of the cup to the mouth and chin and the cup's disposition in a nearly horizontal position without the spilling of the content of the cup, which obviously enables the patient to drink from the cup with little or no raising of the head.

Another feature of the invention is that the spout conforms in shape to the lips.

Another feature of the invention resides in the aforesaid indentation, forming as it were, a dam to control the flow of liquid from the cup until it is properly fitted to the mouth and which then does not interfere with the discharge of the liquid from the cup to the patient in the further elevation of the cup from its initial tilted position.

2

A further feature of the invention resides in the construction of the cup so that all interior surfaces thereof are so disposed that the cup upon inversion will readily drain and as a corollary thereof the interior of the cup can also be readily and thoroughly washed and if desired sterilized.

Other objects and features of the invention will be set forth more fully hereinafter, as for example, the cup illustrated and described herein may have one or more handles applied thereto to facilitate utilization.

The handleless cup for children can be readily grasped by both hands, applied to the mouth in partially tilted position and then further tilted upwardly for the dispensing. The cup is of such size normally that an adult having one hand can readily grip the same, transport it to the lips, further tilt the same for drinking and then return the cup to the support, following the drinking operation.

It will also be apparent from the foregoing that the present invention is particularly helpful to patients that have paralyzed lips or tongues who ordinarily cannot obtain liquid by using the conventional drinking tube which requires a suction action to elevate the liquid from the vessel to the mouth.

The full nature of the invention will be understood from the accompanying drawings and the following description and claims:

In the drawings Fig. 1 is a central sectional view embodying the invention.

Fig. 2 is a top plan view thereof.

Fig. 3 is a front elevation.

In Fig. 1 of the drawings, 10 indicates a vessel bottom that herein is shown flat but it might have any desired cross-sectional form so long as it is self sustaining on a flat surface. 11 indicates a cylindrical like side wall which has a shorter longitudinal element at the rear as indicated at 12. This side wall as the same extends forwardly, is progressively elevated as indicated at 13. The higher portions in these side walls are connected by a bridging top portion 15. Herein the latter is extended rearwardly and downwardly along the side walls to form the slightly upwardly inclined flange 16 which bridging cover and flange define the filling and draining opening 17 in the upwardly inclined top structure. The forward side wall 18, see more particularly Figs. 1 and 3, is slanted inwardly as indicated at 19 and near the top of such indentation is directed upwardly and outwardly as at 20. The upper outward adjacent edges defining the inwardly slanted portion of the forward side wall

are joined together as at 21, see Fig. 2, to form a spout structure 22, having the elliptical like discharge or dispensing opening 23, beaded at 23^a which constitutes the mouth.

By way of example only, if the vessel shown be filled about two-thirds full, it is necessary to tilt the vessel approximately 40° before vessel contents will discharge from the mouth. If the vessel be filled about one-half full it is necessary to tilt the same about 60° before vessel contents discharge from the mouth. The reason for this discharge deferment is because the re-entrant portions 19 and 20 provide a control dam and the level of the water must pass over the greatest indented portion before the liquid can discharge from the mouth.

The present invention also, it will be noted, see Figs. 1 and 2, particularly, is so arranged that the spout and mouth do not project beyond the outlines of the bottom 10 or the body portion of side wall of the vessel 11-13. Thus, even if the vessel be made of readily fracturable material such as china or glass, there are no projecting portions that can be accidentally broken off. The vessel as illustrated, of course, can be made of these materials and can be made of metal or any other suitable material.

The indentation 19 and 20 is given by way of example only for it is quite apparent that for a children's cup the linear dimensions or length of the indentation might be shortened since the distance between the lower lip and the bottom of the chin is less than that of an adult. The degree of indentation, as stated, determines the extent of the damming action.

It will be apparent that for drinking purposes the upper lip engages the top 15 immediately adjacent the mouth 23 and the lower lip engages the indented portion 20 immediately adjacent said mouth, while the chin end is accommodated by the indented portion 19 near the lower end thereof.

It will also be apparent that the vessel can be drained by inverting the same and when so inverted there is no pocket formation that can trap any liquid theretofore in the cup.

It will also be apparent that for cleansing and sterilizing, the cup may have the opening 17 disposed about the discharge end of a faucet and the faucet discharging hot or cold water or a mixture will substantially pressure flush the throat 22 and cleanse said throat when the cup is nearly inverted.

The beading 23^a for invalid use provides a tooth-stop so that the patient can clamp the neck immediately adjacent the mouth by the teeth to facilitate holding of the vessel without slippage thereof from the lips. Also when the vessel is made of metal such beading will prevent lip cutting by sharp edges. Also when made of glass such beading permits the forming of an initial tube extension for severance and grinding to form a smooth finished bead at the mouth.

While considerable emphasis has been placed upon this beading it is to be understood that the inclusion thereof is optional as desired or required.

While considerable emphasis has been placed on the elliptical like discharge opening when de-

sired or when required for production purposes, this opening can be circular or nearly circular in outline, all without departing from the major features of this invention.

5 While the invention has been illustrated and described in great detail in the drawings and foregoing description, the same is to be considered as illustrative and not restrictive in character.

10 The several modifications described herein as well as others which will readily suggest themselves to persons skilled in this art, all are considered to be within the broad scope of the invention, reference being had to the appended claims.

15 The invention claimed is:

1. A handleless drinking vessel comprising a hollow cylindrical body portion having a closed bottom, the body portion providing sides and having at its upper edge, inclining upwardly from 20 opposite sides, a partial top closure portion bridging the upper edges near the uppermost portions of said sides, the body wall immediately contiguous to the edge portion of the closure portion forming therewith a dispensing mouth, said immediately contiguous body wall below said mouth being substantially flat transversely and having a reentrant concave surface roughly cylindrical about a transverse axis and extending from beneath said mouth to a point spaced from the bottom for lower lip accommodation and comprising a discharge controlling dam, said reentrant body portion adjacent the mouth including an inwardly and downwardly directed curved wall portion and adjacent the bottom including an 30 inwardly and upwardly directed curved wall portion, said two curved portions merging one with the other.

2. A drinking vessel as defined by claim 1 wherein the upper curved wall portion has a curvature radius smaller than the curvature radius of the lower curved wall portion.

3. A drinking vessel as defined by claim 2 wherein said mouth has an elliptical like outline disposed cross-wise of the vessel and within 45 the projected outline thereof.
